UNITED STATES PATENT OFFICE.

JOSEPH C. LOYER AND OLIVER M. LOYER, OF DETROIT, MICHIGAN.

MACHINE FOR MAKING COMPOSITION SHINGLES.

1,273,388.

Specification of Letters Patent. Patented July 23, 1918.

Application filed November 26, 1917. Serial No. 203,929.

To all whom it may concern:

Be it known that we, JOSEPH C. LOYER and OLIVER M. LOYER, citizens of the United States, residing at Detroit, county of Wayne, 5 State of Michigan, have invented a certain new and useful Improvement in Machines for Making Composition Shingles, and declare the following to be a full, clear, and exact description of the same, such as will 10 enable others skilled in the art to which it pertains to make and use the same, reference being had to the accompanying drawings, which form a part of this specification.

This invention relates to machines for 15 making composition shingle, and its general object is to provide a comparatively simple and efficient apparatus for making a tapered shingle formed of an asphalt composition on an asphaltum felt or paper base whereby 20 the shingle may be formed rapidly and at a minimum cost. A feature of the invention is involved in a means whereby shingles are formed with a tapered body of asphalt composition on a flat paper or felt base. A further 25 feature of the invention is involved in the means for positioning the asphaltum paper or felt cover on a portion of the upper surface and in a means for applying crushed slate or stone to the upper surface. 30 These and other objects and the several novel features of the invention are hereinafter more fully described and claimed and shown in the accompanying drawings in which—

Figure 1 is a side elevation (practically 35 diagrammatic in form) of a machine embodying our invention.

Fig. 2 is a section taken on line $x-x$ of Fig. 1, showing the forming rolls.

Fig. 3 is a detail of the rolls utilized in 40 cutting the sheet asphaltum, felt or paper into longitudinal strips prior to introduction between the forming rolls.

Fig. 4 is a section taken on line $y-y$ of Fig. 1, showing the rolls for forming the 45 butts of the shingles.

Fig. 5 is a longitudinal section of a shingle.

Fig. 6 is a diagrammatic view of the device for cutting the strips transversely.

50 The machine consists of a series of rolls of various characters as hereinafter described, mounted in any suitable framework, for instance such as is illustrated in Fig. 1. At one end of the framework is mounted a pair of cutter rolls 1 and 2, which may be 55 of any approved form adapted to cut a sheet

of material delivered thereto from the roll 3 into longitudinal strips of a width equal to the length of the shingle to be formed. The asphaltum paper or felt roll 3 is the 60 same in character as now commonly used in the manufacture of roofing material, and preferably the roll 3 and sheet of paper thereon is of a width equal to the length of four shingles for reasons as will appear 65 hereinafter.

There is a traveling belt 4 carried on rolls 5 and 6 mounted in the framework and these rolls are driven by means of a main drive shaft 7 and pair of bevel gears 8 and 9 and vertical shaft 10 on the upper end of which is a gear 11 meshing with a gear 12 on the end of the roll. Each roll 5 and 6 is driven by a single train of gears and shafting, and all of the rolls as hereinafter described, are 70 driven in like manner from the main shaft 7. The belt rolls are mounted so that the lower half of the belt runs in a tank 13 containing water to keep the belt saturated. The belt rollers 5 and 6 are cylindrical in 75 form so that the belt in passing over the rolls lies flat, but the said rolls are grooved to receive longitudinal strips 14 secured to the under side of the belt for the purpose of giving strength thereto. The belt is preferably of woven fabric, and by use of the longitudinal strips 14 the belt is prevented from stretching materially. The strips 14 may be formed of material such as hydraulic 80 packing and preferably in one piece with 85 lapped ends.

What we have termed the forming roll is indicated at 15 in Fig. 1 and, as will be seen in Fig. 2, this roll is formed of several independent hollow members 15^a tapered in 90 form and mounted on a shaft 23. There are preferably four of the rollers 15^a with the small ends of the two pairs placed together and the large ends of the two inner rolls being contiguously positioned. While only 95 two pairs of rolls 15^a are here shown, it is to be understood that any desired number of rolls may be used. These rolls are formed at the ends to provide a groove 16 in which the strips 14 on the belt may ride. Above 100 this composite roll 15 is mounted a pressure roller 17 which is adjustably mounted in the framework to enable it to be regulated in position relative to the roll 15 so that the material placed on the belt may be shaped to 105 the desired thickness. The composite roll 15 is driven by means of a gear 18 on the main 110

shaft and a bevel gear 19 on the vertical shaft 20. On this shaft 20 is a bevel gear 21 engaging a similar bevel gear 22 on the shaft 23 of the roll 15. Above this gear 21 is a gear 24 splined on the shaft 20 meshing with a gear 25 on the shaft 26 of the pressure roll 17. The shaft 26 is carried in boxes 27 on opposite sides of the vertical framework 10^a slidable by means of the 10 screws 28 and 29 to adjust the position of the roll 17. The rolls 17 and 15, by the train of gears mentioned, are driven in opposite directions as will be readily understood. The roll 17 is provided with three flat edged 15 blades 30 positioned to engage against the belt running between the rollers at the points below which the strips 14 are fastened. These blades 30 are preferably about one inch in width of face, and serve the 20 purpose of holding the paper in position on the belt after being cut by the rollers 1 and 2. From Fig. 2 it will be understood that the paper coming from the roll 3 passes through the cutting rolls 1 and 2 and is slit 25 longitudinally, the cutting rolls 1 and 2 as will be seen in Fig. 3 having cutters 31 in the upper roll 1 riding in grooves 32 in the lower roll 2, and these knives 31 are spaced the same as the blades 30 on the roll 17. The 30 paper in passing onto the belt 4 lies flat as does the belt in passing over the roll 5. As the belt and paper pass between the rollers 15 and 17, however, the belt and the paper strips are depressed by the blades 30 to conform 35 to the outline of the composite roll 15. As will be readily understood the blades 30 ride on the contiguous edges of the two adjacent strips of paper and thus holds the paper in position on the belt, each pair of 40 contiguous strips being opposite inclined.

Suitably supported in any approved manner above the belt roll 5 is a mixer 33 into which asphalt and cinders or the like is delivered through the chutes 34 and 35 respectively. This is thoroughly mixed together by means of the usual mixing blades 90 in the mixer 33 operated by means of a belt wheel 36. By rotation of the mixing blades, the material is passed through the 45 mixer and delivered therefrom by means of a chute 37 onto the upper surface of the paper or felt strips carried on the belt 4. The chute 37 and mixer should deliver a sufficient quantity of material and fairly equally 50 distribute it across the face of the belt to provide the desired thickness of material after passing through the rolls. As will be understood from Fig. 3, the upper face of the asphalt and cinder composition will be 55 practically flat entirely across the rolls 17 and 15 and that on each strip of paper on any section of the composite roll 15 the material is of certain thickness at one end and considerably thinner at the other. This is 60 shown somewhat in exaggerated form in

Fig. 2, and in the finished product the greatest thickness of material and the felt at one edge should be about three thirty-seconds of an inch and at the other edge about five-sixteenths of an inch conforming practically to 70 usual practice as to the thickness of the top and butt end of a shingle.

The material in passing in between the rolls 15 and 17 is compressed on the paper or felt web, and being delivered thereonto in a 75 warm state is readily shaped as described. Furthermore, the roll 17 is heated and this may be accomplished by extending longitudinally of the face of the roll a gas pipe 80 having apertures on the side adjacent the 85 face of the roll, and the flame impinges against the face of the roll thus heating the same and tending to maintain the material hot during the forming thereof. The blades 30 on the roll 17 hold each two adjacent belt 90 or paper webs in the form of a trough which is readily filled with the hot asphalt composition. The material and paper strips after passing through the rolls 15 and 17, next pass between a similar pair of rollers 39 and 40. The roll 39 is composite in form corresponding to the roll 15, and the roll 40 is a heated roll exactly similar to the roll 17 although, if desired, the blades 30 used on the roll 17 may be dispensed with as the material on the belt formed between the first pair of rollers 15 and 17 will hold the belt in angular position on the rolls 39. The roll 40 is heated in the same manner as the roll 17 for the reason that the material is quite hot 100 and apt to bubble in passing the roll 17. The distance between the rolls 17 and 40 is sufficient to allow the coating to partially cool. Then the hot roll 40 makes the material sufficiently plastic to fill the depressions 105 and produce a flat surface.

It is to be noted that the screw members 28 and 29 are carried by an upper framework 77 which is provided with brackets 41 for the screws and this framework also 110 carries a series of asphaltum paper rolls 42 there being a roll 42 for each division of the composite roller 15. These rolls are of felt or paper exactly similar to the asphaltum paper in the roll 3 and having a 115 width in the neighborhood of one-half the length of a section 15^a of the roll 15. These rolls 42 are positioned so that the paper may be fed therefrom onto the narrow side of each coated strip passed between the rolls 39 and 40. The paper passes from the roll 42 over a cold roller 43 mounted in the main framework and its purpose is to press the strips from the roll 42 into the surface of each longitudinal composite strip 120 passing between the rolls 15 and 17 and 39 and 40. This will be understood from Fig. 5 showing the section of a shingle on the lower side of which is the strip 44 on which the asphalt and cinder composition 46 is 125 130

placed and shaped by means of the rollers 15 and 17, and as this composite felt or paper and composition strip passes between the rolls 43 and companion roll 47 therebelow this upper strip 48 from the roll 42 is forced into the upper face of the composition so that the upper face of the felt or paper strip 48 and exposed face of the asphalt and cinder composition are in the same plane. The roll 47 is a composite roll the same as the rolls 15 and 39, and the cold rolls 43 and 47 serve to set the composition introduced therebetween after passing beneath the hot roll 40. The necessity 15 of embedding the upper strip 48 in the face of the composition as indicated in Fig. 5 is to enable the superimposed shingle to lie flatly in contact one with the other as shown in dotted lines in the said figure. The 20 butt of the said shingle extends slightly beyond the lower end of the strip 48 and leaving exposed only the asphalt-cinder face of the lower shingle and the asphaltum paper or felt 44 on the lower face of the 25 upper shingle lies in surface contact with the felt or paper strip 48 on the upper surface of the lower shingle, and when laid the two shingles unite to a greater or less extent by reason of the contact of the asphaltum coated felt or paper. Thus the shingles are prevented from warping or lifting after being laid.

After passing between the rolls 43 and 47 the longitudinal strips which have been shaped as stated, and as shown in cross section in Fig. 5, pass beneath a gas burner 49 positioned above the belt having flame or arranged to produce sufficient heat to make the upper surface of the asphalt 40 sticky in character. Although the drawing shows this gas burner 49 as being quite close to the rolls 43 and 47 it is in fact spaced some little distance therefrom, being practically about four feet from the center of the rolls. Directly above the burner is a bin 50 containing crushed or granular slate or stone. The bin has a tapered bottom wall and at the discharge end is provided with an agitating device (not here 45 shown) operated by the wheel 51 which is driven by means of a similar wheel on the shaft of the roller 43. The agitator operated by the wheel 51 is thus continuously operated during the operation of the machine and the quantity of crushed slate or 50 stone falls down through the burner 49 onto the asphalt covered strips. The material in falling through the burner is heated to some extent and falls directly 55 onto the sticky upper surface of the composition and naturally adheres thereto. After the strips pass from beneath the heater 49, they next pass beneath a series 60 of air nozzles 52 (there preferably being 65 a nozzle for each coated strip), and by this

means the excess slate or stone is blown off from the surface of the composition. Thereupon the strips pass between the rollers 53 and 54, the roller 53 being preferably similar to the roller 17 and the roller 54 70 being composite in form similar to the roll 15. These rolls 53 and 54 are cold rolls and serve to further embed the adhering granular stone or slate into the asphalt surface. It is to be noted that crushed stone or slate 75 do not to any material extent adhere to the upper paper strip 48 but do readily adhere to the sticky asphalt portion 46.

After the strips have passed between the rolls 53 and 54 the belt 4 passes around the 80 belt roller 6 and the coated strips only pass on between the forming rollers 55 and 56, shown in Fig. 4. The roller 55 is provided with a pair of formers 57 and 58 which run between adjacent thick edges of each pair of 85 strips and shape the asphalt material on the edge to conform to the curved portion 59 of the formers, as is indicated at 90 in Fig. 5. They also serve to prevent the asphalt strips from sticking together. Centrally disposed of the roll 55 is a parting member 60 that separates the two adjacent thin edges of the central strips and serves to produce a smooth and straight edge on the said strips. In passing through these 95 rollers 55 and 56 therefor the thick longitudinal edges of the strips are shaped to conform to the desired shape of the butt of a shingle. After passing through the rolls 55 and 56, the upper surface of the 100 coated strips should be sprayed with cold water which may be supplied through pipes 91. After passing through these rolls 55 and 56 these longitudinal strips pass between the cutting rolls 78 and 79. The 105 roll 78 is provided with a pair of cutters extending longitudinally thereacross as shown in detail in Fig. 6. These blades are spaced apart a distance to produce a shingle of the desired width in cutting 110 the webs transversely, there being two shingles severed from the strips during each revolution of the roll 78. These fall down from the machine onto an inclined table, a portion of which is indicated at 99. 115 The roller 78 is driven by means of a bevel gear 70 on the main shaft 7 meshing with a bevel gear 61 on a cross shaft which is provided with a spur gear meshing with a large spur gear 62 on the shaft 63 extending transversely of the machine. On the shaft 63 is a spur gear 64 meshing with a spur gear 65 on the shaft of the cutter 78. The gears 62, 64 and 65 are indicated by double lines, it being understood that teeth 120 are cut therein (though not here shown). The time of rotation of the cutter 78 exactly accords with the speed of movement of the strips through the machine, and thus paper and material fed into the machine at 130

the forward end is delivered therefrom in the form of finished shingle.

By maintaining the belt 4 saturated as stated, the asphalt is prevented from sticking thereto and furthermore, the belt by being continuously saturated is prevented from being injured by the heat from the rolls 17 and 40. While we prefer to utilize asphalt as a base of the composition, other material may be used if desired and may be mixed with various materials other than cinders mentioned. We prefer, however, to utilize asphalt by reason of its long life and waterproof quality and also prefer to utilize crushed cinders as the cinders are inexpensive and readily secured and are practically fire proof in character. The paper cutting rolls shown in detail in Fig. 3 are to be understood as being positively 20 driven by any approved mechanism in such manner that the surface speed thereof is at least equal to the speed of travel of the strips through the machine.

It is preferable to use a water spraying device beneath the belt at points just below the hot rolls 17 and 40. Such device may be provided by a pipe indicated at 95 in Fig. 1 apertured on the side adjacent the rolls 15 and 39. This serves to keep the belt saturated and the paper strips and such portions of asphalt as may come in contact with the belt are prevented from adhering thereto. Such spray device may also be used in conjunction with the rolls 47 and 54 as indicated in Fig. 1.

It is also preferable to utilize a belt support indicated at 96 between the several pairs of rollers to prevent a sagging thereof. This support may be of any approved form adaptable for the purpose. Preferably, grooved longitudinally to receive the longitudinal strip 14 on the belt.

The asphaltum felt or paper strips on which the asphalt composition is placed is preferably somewhat thicker than the strip embedded in the upper surface of the composition. A comparatively thin strip may be utilized for the upper surface, its purpose being particularly to provide a portion of the upper surface of the shingle of a character to adhere to the bottom of the superimposed shingle as heretofore stated and indicated in Fig. 5. The strength of the shingle is provided by the comparatively heavy strip on which the asphalt is poured.

The above description is of the preferred form of mechanism for making the described shingle, and it is to be understood that various departures in the way of details of construction of the various parts may be utilized without departing from the spirit of this invention.

Having thus fully described our inven-

tion, its utility and mode of operation, what we claim and desire to secure by Letters Patent of the United States is—

1. In a machine for making composition shingles, a traveling belt, forming rollers between which the belt travels adapted to shape the belt into a series of longitudinally extending depressions and elevations providing transverse angularly positioned surfaces, means for feeding strips of asphaltum felt, paper or the like on each of the said inclined surfaces, means for applying a plastic composition to the upper surface of the strips, the forming rollers shaping the material in tapered form transversely of each strip, and means for severing the several strips transversely to form shingles of the desired width.

2. In a machine for making composition shingle, a traveling belt, forming rollers between which the belt travels adapted to shape the belt into a series of longitudinally extending depressions and elevations providing surfaces lying at an angle to the horizontal transversely of the belt, means for feeding a series of webs on each of the said inclined surfaces, means for applying a plastic composition to the upper surface of the webs, the forming rollers shaping the material in tapered form transversely of the webs, means for applying a paper or felt strip on a portion of the upper surface of the formed composition, and means for severing the several webs transversely to form shingles.

3. In a machine for making composition shingle, a traveling belt forming rollers between which the belt travels adapted to shape the belt into a series of longitudinally extending depressions and elevations providing surfaces lying at an angle to the horizontal transversely of the belt, means for feeding a continuous web on each of the inclined surfaces, means for applying a cementitious composition to the upper surface of the webs, the forming rollers shaping the material in tapered form transversely of the webs, means for shaping the edges of the strips during movement thereof, and means for severing the several webs transversely to form shingles.

4. In a machine for making composition shingle, a traveling belt, forming rollers between which the belt travels adapted to shape the belt into a series of longitudinally extending depressions and elevations providing surfaces lying at an angle to the horizontal transversely of the belt, means for feeding a web formed of asphaltum paper or felt on each of the said inclined surfaces with the edges thereof practically in contact, means for applying a cementitious coating to the upper surface of the webs prior to their introduction between the rolls,

- said rolls shaping the coating in tapered form transversely of the strips, means for applying powdered slate or the like to the upper surface of the strips, and means for 5 severing the several webs transversely to form shingles.
5. In a machine for making composition shingle, a traveling belt, forming rollers between which the belt travels, the roller 10 beneath the belt being formed of a series of cones presenting oppositely inclined surfaces transversely of the belt, means for applying asphaltum paper or felt strips with the edges thereof in contiguous relation to 15 the belt and over the inclined surfaces of the forming rollers respectively, the said belt being flexible transversely thereof, means for applying plastic composition to the upper surface of the strips, the said material and 20 strips in passing through the rollers forcing the belt into contact with the transversely inclined surfaces, the upper forming roller being cylindrical whereby the upper surface of the material on the several strips is rolled 25 flat, means for heating the cylindrical roller, a second set of forming rollers similar in character to the first set, means for applying heat to the cylindrical roller of the second set, means for applying a strip of asphaltum 30 felt or paper on the upper surface of each of the said plastic coated strips, the said upper strip being less in width than the width of the coated strips, means for embedding the 35 said upper strips in the plastic composition, and means for severing the several strips transversely to form longitudinally tapered shingles.
6. In a machine for making composition shingle, means for coating a web of asphaltum felt or paper with a plastic composition 40 tapering transversely of the web or strip, means for applying a strip of asphaltum felt or paper to the surface of the composition and covering a portion of the strip from the 45 narrow edge, and means for severing the strip transversely to form longitudinally tapered shingles.
7. In a machine for forming composition shingle, means for applying a plastic coating 50 to a web or strip of asphaltum felt or paper, means for maintaining the upper surface of the composition in a plastic state, means for applying an asphaltum strip to cover a portion of the plastic composition 55 while in the plastic state, means for applying granular slate or stone to the plastic surface, means for embedding the stone in the said plastic surface, an air blast for blowing excess granular slate or stone from 60 the said surface, means for cooling the composition, and means for severing the com-
- posite strip transversely to form longitudinally tapered shingles.
8. In a machine for making composition shingle, a framework, forming rollers there- 65 in, means for feeding a series of webs or strips of asphaltum felt or paper through the forming rolls, means for applying plastic composition to the surface thereof, the forming rolls shaping the composition in ta- 70 pered form transversely of each of the strips, the strips lying in contiguous relation, means for maintaining the composition on the several strips in separate relation during the forming process, means for shaping the 75 thick edges of the strip, and means for severing the several strips transversely to form longitudinally tapered shingles.
9. The method of making longitudinally tapered composition shingle consisting in 80 coating a continuously moving web of asphaltum felt or paper with a hot plastic composition tapered transversely from one edge of the strip to the other, embedding a strip of asphaltum felt or paper in the up- 85 per surface of the composition to cover a portion thereof on the narrow side, and severing the composite strip transversely to form longitudinally tapered shingles.
10. The method of making longitudinally 90 tapered composition shingle with formed butts consisting in depositing on a traveling web a coating of hot plastic material, forming the material during movement of the web to present a transversely tapered area 95 in cross section, heating the upper surface of the composition after formation, embedding granular or crushed stone or slate in the upper heated surface, removing the excess slate or stone, passing the web through 100 forming rollers adapted to shape the longitudinal thick edge of the strip, cooling and hardening the composition, and severing the strip transversely at intervals.
11. The method of making longitudinally 105 tapered composition shingle, consisting in coating a web with plastic composition, tapering in thickness transversely of the web, embedding an asphaltum paper or felt strip of a width less than that of the plastic composition in the upper surface thereof, and severing the strip transversely at intervals.
12. The method of making composition shingle consisting in coating a traveling web 110 with a plastic composition, embedding a web in a portion of the upper surface of the composition at one edge, and severing the composite strip transversely at intervals.

In testimony whereof we sign this specification.

JOSEPH C. LOYER.
OLIVER M. LOYER.
